W. R. ALLEN.
ADDRESS PLATE.
APPLICATION FILED MAY 8, 1911.

1,088,670.

Patented Feb. 24, 1914.

UNITED STATES PATENT OFFICE.

WILLIAM R. ALLEN, OF CLEVELAND, OHIO, ASSIGNOR TO THE AMERICAN MULTIGRAPH COMPANY, OF CLEVELAND, OHIO, A CORPORATION OF OHIO.

ADDRESS-PLATE.

1,088,670

Specification of Letters Patent. Patented Feb. 24, 1914.

Application filed May 8, 1911. Serial No. 625,858.

To all whom it may concern:

Be it known that I, WILLIAM R. ALLEN, a citizen of the United States, residing at Cleveland, in the county of Cuyahoga and State of Ohio, have invented a certain new and useful Improvement in Address-Plates, of which the following is a full, clear, and exact description, reference being had to the accompanying drawings.

10 The object of this invention is to provide a simple and efficient device for carrying an address made up of individual type, the device being utilizable as a unit in addressing machines, printing machines, etc. It is convenient to refer to the assembled device as an address plate.

15 In its preferred and complete form it comprises a slotted plate, individual grooved type adapted to be carried in the slots, means for holding the type against longitudinal shifting, means for holding the tines caused by slotting the plate in the proper position, and means for conveniently indexing the address carried.

20 One of the features of the present address plate is its embodiment in such form that similar plates may be stacked, one upon another, enabling the convenient withdrawal of the plate, as desired.

25 The invention is hereinafter more fully explained and its essential characteristics are summarized in the claims.

30 In the drawings, Figure 1 is a perspective view of my address plate complete; Fig. 2 is a plan of such plate with the locking bar removed; Fig. 3 is a perspective view of the locking bar itself; Fig. 4 is a bottom plan of a portion of the plate near the ends of the tines; Figs. 5 and 6 are perspective views of two forms of locking clip for holding the type in place; Fig. 7 is a perspective view of one of the indices; Fig. 8 is a diagram, in the nature of an end view, illustrating the stacking of the plates.

35 The body of the complete address plate consists of a single piece of sheet metal 10 slotted from one end by parallel slots 11 and having its sides 12 flanged from the inter-

mediate portion of the plate. If the plate is to be used on a rotary member, the intermediate portion is preferably curved on an arc corresponding to such member and the flanges 12 are more or less nearly radial.

40 indicates type grooved on its opposite sides and adapted to stand in rows in the respective slots 11. The drawing shows three of these slots and the type arranged to make a complete address of three lines, giving the name, the street number and the city. It is to be understood, however, that the number 45 of slots may be varied, as desired. The type may be of the standard Multigraph pattern, having, in addition to the grooves in the sides, the transversely tapered foot or the feet may be plain. In either case, the foot 50 of the type lines on the under side of the plate 10, the head rests on the upper side and the neck occupies the slot.

45 To brace the slotted plate and hold the respective tines thereof in proper position I provide a locking bar 30, shown in Figs. 1, 3 and 8. This bar has in it a series of openings 31 adapted to pass over the ends of the various tines of the plate, and also over the ends of two projections 14 on the end of 55 the plate outside of the outermost slots 11. These two projections 14 are formed with notches 15 in their outer edges. When the locking bar is in place on the end of the plate 10, as shown in Figs. 1 and 8, these 60 notches 15 are occupied by the end portions of the locking bar and, accordingly, the bar is held on the plate against accidental displacement. To put the bar in place, the side portions of the plate are simply pressed together slightly, enabling the bar to be passed over the outwardly hooking ends of the projections 14.

50 It will be seen from Figs. 3 and 8 that each opening 31 in the bar 30 is connected 90 with the lower edge of the bar by a narrower opening 32. This narrow opening 95 lines with the narrow space between the feet of the respective type lines. This enables the plate to seat on projecting parallel strips which support the respective tines

and thereby support the type. These strips may conveniently be the web portions of parallel rails similar to those used in the Multigraph, the heads of the rails being removed. When the plate stands on such webs, the tines of the plate take the place of the heads of the rails.

Fig. 8 shows a series of my address plates surmounted or stacked. It will be seen that the sides 12 of each plate rest their lower edges on the top surface adjacent to the shoulders of the next lower plate with the type and locking bar of each plate out of contact with either of the adjacent plates. Accordingly, it is a very simple matter to slide out longitudinally any plate desired for use. To prevent the displacement of the type 20 in their respective slots, I provide suitable clips made of spring sheet metal and having notches whereby they occupy the slots, the spring of the metal causing the clips to bind against the upper and under surfaces of the tines defining the slots. These clips may be formed in an arc with their legs flaring, as shown at 40^a in Figs. 1, 2 and 6, or they may have the legs projecting diagonally toward each other, as shown at 40^b in Fig. 5. In either case, there are two legs 41 which are notched on opposite edges so that they may be passed into the slots occupied by the type. The spring of the metal causes these clips to bind on the upper and under faces of the tines which they overhang. This frictional binding is sufficient to prevent any accidental displacement of the clips or type. In fact, with either of the clips shown, it is difficult to shove them lengthwise of the slot from above, while on the under side, by taking hold of one leg, the clip may be very easily drawn along. In the form shown in Fig. 5, the spring action tends to bring the legs more nearly together than they assume when in position, while in the form in Fig. 6 the spring action tends to straighten the clips or bring the legs farther apart than the normal. In either case, the displacement from the active position by engagement with the free end of the leg allows it to be easily shifted, while, when released, the clip locks itself in place due to the binding action of the upper and under edges of the notches.

To enable the tines to be accurately positioned for loading, should they become displaced, I form on the under side of each tine, near its free end, a V-shaped groove, as shown at 17 in Fig. 4. When the block, to be loaded, is placed with its free edges on properly positioned, V-shaped stationary centering devices, the tines are automatically shoved, not only upwardly, but laterally, if displaced, so as to come into accurate position for loading.

To enable my address plate to carry an index of the address, I provide a series of

holes 18 in one of the side walls 12, and by means of these holes I secure to such wall one or more index plates 50. These index plates are shown in Figs. 1 and 7 and consist preferably of a body portion and two projecting tongues 51 which are adapted to be bent at right angles to the body portion and passed through the holes 18 and bent over onto the inner side of the wall 12. The adjacent tongues of two adjacent index plates may be passed through the same hole. Fig. 1 shows two index plates which are shown as carrying initial letters corresponding to the two words of the address name. This index feature may be extended, as desired, there being room on the wall 12 to supply the index with the name, city and other data, as may be desired.

It will be seen from the above description that my address plate is not only simple and cheap in construction, but that it is very effective in service, carrying a complete, properly indexed address; that such address is held against displacement in the plate; that the plates may be stacked and shifted one on the other with great ease; and that when it is desired to discard any address, the type may be easily removed from the plate and the plate used for another address. By carrying actual metal type, the complete address plate is endowed with great durability; moreover, by the use of such type an imprint in imitation of typewriting, if desired, may be easily obtained. The address may be caused to print with the body of a letter, printing an addressed letter at one impression, or it may be used for supplying addresses at a different time to a letter, or for printing addresses alone. By arranging the plates with slots carrying grooved metal type, the type may bear on their shoulders on the top of the plate and the bottom of the plate between the type lines may bear on ribbed supports, so that the type may be accurately supported at the proper height-to-paper; and, by having the tines of a size and shape corresponding to the heads of rails in the Multigraph, my plate may be used in such machine by removing the heads of rails and allowing the plate to rest on the remaining webs.

Having thus described my invention, what I claim is:

1. An address plate comprising a member having a plurality of slots adapted to hold a plurality of rows of grooved individual type, and a removable locking bar common to the tines between the slots of said member.

2. In a device of the character described, the combination of a plate slotted by a plurality of slots from one end, and a removable continuous transverse bar adapted to engage an intermediate tine and outside tine at their free ends.

3. In an address plate, the combination of a plate slotted from one end providing tines, hooks on the end of the plate portions outside of the tines, and a transverse bar having openings for such hooks and openings for the ends of the respective tines. 70
4. In an address plate, the combination of a plate slotted by a plurality of slots from one end and thus providing external and 10 intermediate tines, the external tines being recessed to make their end portions hooked, and a transverse bar having openings to receive such tines. 75
5. In an address plate, the combination of a plate slotted from one end and thus providing tines, a movable transverse end bar having openings to receive such tines, and means on the side portions of the plate outside of the tines to lock the bar in place. 80
6. In an address plate, the combination of a plate slotted from one end and thus providing tines, and a transverse bar having openings to receive such tines, there being openings from the lower edge of the 20 bar into the tine openings referred to, such lower edge openings registering with the space beneath the tines. 85
7. The combination of a metal plate slotted from one end, grooved type carried in such slots, and a locking bar extending transversely of the plate and having openings engaging the respective tines, said locking bar extending above the plate to a less distance than the printing face of the 30 type. 90
8. In an address plate, the combination of a plate having parallel slots, grooved individual type carried in such slots and projecting above and below the same, down- 40 turned edges at the two sides of the plate projecting below the feet of the type, and a transverse bar at the end of the plate secured to the body of the plate and having openings for receiving the respective tines. 95
9. In an address plate, the combination of a metal plate having a segmental intermediate portion with projecting edge flanges, an index carried by one of the edge flanges, longitudinal slots in the segmental 50 portion, and individual type in such slots. 100
10. The combination of a plate having down-turned edges and intermediate slots having tines between them, a brace for the free ends of said tines, and an index device 55 on one of the down-turned edges. 105
11. The combination of a slotted plate having a flanged edge, a series of aligned holes through such edge, index plates each provided with a pair of tongues, said 60 tongues projecting inwardly through holes in the edge. 110
12. In an address plate, the combination of a slotted plate, grooved type in the slots, spring metal clips for preventing the longitudinal movement of a type, each clip hav- 65 115
- ing two legs with lateral notches therein positioned to require relative displacement of the legs to enable them to slide on the tines, whereby when at rest the legs bind on the tines of the plate. 120
13. The combination, with a holder for a line of grooved type, of a clip for limiting the position of such line, said clip being an approximately U-shaped spring having two legs, each with a pair of notches therein, 70 the normal position of said legs tending to cause the clip to bind on said holder. 125
14. The combination, with a slotted member adapted to carry grooved type, of a spring clip for limiting the position of a line of such type, said clip being an approximately U-shaped piece of sheet metal having notches in its legs and tending to assume a position to bind on the upper and under sides of said member. 80
15. The combination, with a pair of parallel separated guiding edges adapted to hold between them a row of type grooved on their opposite sides with the edges occupying the grooves of the type, of a clip 90 for limiting the position of such row, said clip comprising a two-legged spring with a notch in each leg, the legs being normally out of parallelism and the notches being of less height than the diagonal distances 95 through the guiding edge measured in the normal planes of said legs, whereby the legs must be relatively displaced to slide on such guiding edge. 100
16. An address plate having a plurality of tines with V-shaped grooves on one face whereby they may be accurately positioned. 105
17. An address plate having a plurality of tines with V-shaped grooves on one face whereby they may be accurately positioned combined with a locking bar having openings to receive such tines and hold them properly spaced. 110
18. An address plate having a body portion slotted to hold type projecting above and below the plate, a recessed cross bar adapted to engage and hold the tines provided by the slots at one end of the plate, the plate having its edges projecting downwardly a greater distance than the downward projection of the type or cross bar. 115
19. In an address plate, the combination of a segmental plate having parallel slots extending from one end, grooved individual type carried in such slots and projecting above and below the same, down-turned radial edges at the two sides of the plate projecting below the foot of the type, and a removable transverse bar at the end of the plate held by hooked projections to the body 120 of the plate and having openings for receiving the ends of the respective tines between the slots. 125
20. The combination, with a holder for a line of grooved type, of a clip for limit- 130

ing the position of such line, said clip being an approximately U-shaped spring having two legs, the ends of which are free, each leg having a pair of notches therein, the 5 position of said legs when the clip is engaging type in the holder bringing the shoulders both above and below the notches into engagement with upper and under surfaces

of the holder and causing the clip to bind on said holder.

In testimony whereof, I hereunto affix my signature in the presence of two witnesses.

WILLIAM R. ALLEN.
